UNITED STATES PATENT OFFICE.

BENJAMIN FRANKLIN McCRAITH, OF LARK, NORTH DAKOTA.

ALLIGATOR-WRENCH.

1,304,584.

Specification of Letters Patent.

Patented May 27, 1919.

Application filed July 22, 1918. Serial No. 246,132.

To all whom it may concern:

Be it known that I, BENJAMIN FRANKLIN McCRAITH, a citizen of the United States, residing at Lark, in the county of Grant, 5 State of North Dakota, have invented certain new and useful Improvements in Alligator-Wrenches; and I do hereby declare the following to be a full, clear, and exact description of the invention, such as will 10 enable others skilled in the art to which it appertains to make and use the same.

This invention is an improvement in tools and has particular reference to a wrench.

An object of the invention is to provide 15 an improved wrench of simple, effective and inexpensive construction wherein the jaws thereof are so formed as to render the tool adaptable to various uses such as a nut and pipe wrench.

20 The inventive idea involved is capable of receiving a variety of mechanical expressions one of which, for the purpose of illustrating the invention, is shown in the accompanying drawing wherein:

25 Figure 1 is a side elevation of the wrench constructed in accordance with the invention.

Fig. 2 is a vertical longitudinal sectional view showing the adjustable auxiliary jaw 30 or bit member of the wrench in inoperative position.

Fig. 3 is a similar view showing said auxiliary jaw in its operative position.

Fig. 4 is a perspective view of the auxiliary jaw.

The wrench is shown in what is now believed to be its preferred form which comprises a handle portion 5 upon one end of which is formed one of the main jaws 6 40 having a straight gripping edge or surface 7 at the inner end of which is disposed a pair of pivot ears 8 between which is pivoted the other main jaw 9 of the wrench. The gripping edge 10 of the jaw 9 is preferably 45 serrated to form a better gripping surface which co-operates with the surface 7 to grip a pipe or nut.

In order to adjust the jaw 9 relative to the jaw 6 there is provided a screw member 11 50 mounted in the handle portion 5 and extending laterally therefrom and provided with a milled head 12 reset within the handle portion whereby the screw member may be rotated. The shank 13 of the jaw 9 has connected thereto for sliding movement thereon 55 a clip 14 having a screw threaded opening

15 for receiving the screw member 11 so that when said clip is rotated said clip will be adjusted longitudinally thereof and move the jaw 9 about its pivot between the ears 60 8 and toward and away from the jaw 6.

The jaw 6 is preferably enlarged as indicated at 16 and is provided in its enlarged portion with an elongated recess 17 which extends obliquely with respect to the longitudinal axis of the jaw and the outer end of said recess opens upon the gripping surface 7 of the jaw and the outer end thereof. The inner end of the recess 17 communicates with a non-threaded opening 19 which extends 70 through the enlarged portion 7 in alignment with the recess 17 and opens upon a shoulder 20 having a cutaway portion or recess 21 contiguous thereto. The recess 17 is preferably rectangular in formation and has 75 slidably mounted therein an auxiliary jaw or bit member 22 provided with a gripping surface 23 and the outer end of said auxiliary jaw is beveled as indicated at 24. Extending from the inner end of the jaw 22 in 80 alignment with the longitudinal axis thereof is a screw threaded stem or shank 25 mounted in the opening 19 and projecting beyond the outer end thereof. A milled nut 26 is threaded upon the projecting end of the 85 stem or shank 25 and engages the shoulder 20 and also the recess 21 which latter prevents accidental detachment of the head or nut 26 from the stem and maintains said nut in such position that rotation thereof will 90 cause an adjustment of the stem 25 and consequently the jaw 22 longitudinally in the recess 17. When the parts are in the position shown in Fig. 2 with the auxiliary jaw 22 located within the recess 17 and in its inoperative position, the device is best adapted 95 as a pipe wrench but should it be desired to adjust the same to a nut wrench, the nut or head 26 may be rotated to adjust the jaw 22 outwardly and longitudinally of the recess to the position shown in Fig. 3 with the outer end of the jaw 22 projecting beyond the gripping surface of the jaw 6. When in such position and the gripping surfaces 10 100 and 23 are engaged with a nut, the latter 105 surface will be in parallel relation with the former and will therefore effectively engage the sides of a nut in order that the same may be readily turned.

It will thus be seen that the jaws of the 110 wrench are disposed in normally divergent relation and are capable of relative angular

adjustment through the medium of the connection so that by turning the nut 12, the jaws are not only adjusted to be held in adjusted position but may be employed to 5 engage a pipe when the auxiliary jaw is disposed or confined within the jaw 7, as shown in Fig. 2 of the drawings. However, when the auxiliary jaw 22 is adjusted in a manner shown in Fig. 3 of the drawings so 10 as to project from the working face of the jaw 7, it will be disposed substantially parallel to the working face of the jaw 9 so as to effectively grip a nut or other object of polygonal cross section.

15 What is claimed is:—

1. A wrench of the class described comprising a pair of main jaws pivotally connected at adjacent ends thereof and disposed with the gripping faces thereof in divergent 20 relation, and an adjustable jaw carried by one of said main jaws and movable obliquely with respect to the longitudinal axis and gripping surface thereof and provided with a gripping surface adapted to coöperate with 25 the gripping surface of the other main jaw and adapted to lie substantially parallel thereto when adjusted to project from the jaw by which it is carried.

2. A wrench of the class described comprising coöperating main jaws having gripping surfaces disposed in divergent relation, one of said jaws having a recess arranged obliquely with respect to the longitudinal 30 axis thereof, one end of said recess opening upon the gripping surface of said jaw, the latter jaw also having a non-threaded opening 35 communicating with said recess and extending longitudinally thereof, a stem

mounted in said non-threaded opening and adjustable longitudinally thereof, and an auxiliary jaw carried by one end of said stem and slidably mounted within said recess and adapted to be positioned entirely therein when in its inoperative position, said auxiliary jaw being adjustable to its operative position by the adjustment of said stem and having a gripping surface adapted to coöperate with the gripping surface of the other main jaw and disposed substantially parallel to it. 40

3. In a wrench, the combination with jaws having the gripping faces thereof disposed in divergent relation, of an auxiliary jaw carried by one of the jaws and movable obliquely thereof to project from the gripping face of said jaw substantially parallel 50 to the gripping face of the other jaw and spaced therefrom. 55

4. In a wrench, the combination with pivoted jaws of a pipe wrench and means to adjust and hold the same in adjusted position relative to one another; of an auxiliary jaw of polygonal cross section adjustable movably into and out of the other jaw through the gripping face thereof and adapted when 60 projected to disturb the line of continuity of the gripping face of the jaw by which it is carried so as to lie substantially parallel with the gripping face of the other jaw. 65

In testimony whereof, I affix my signature, 70 in the presence of two witnesses.

BENJAMIN FRANKLIN McCRAITH.
